J. L. Stetson.

UNITED STATES PATENT OFFICE.

JEAN LANGUEREAU, OF PARIS, FRANCE.

HOLDER FOR INCANDESCENT ELECTRIC LAMPS.

SPECIFICATION forming part of Letters Patent No. 293,256, dated February 12, 1884.

Application filed July 23, 1883. (No model.)

To all whom it may concern:

Be it known that I, JEAN LANGUEREAU, a citizen of the Republic of France, residing at Paris, in the Department of the Seine, France, 5 have invented certain new and useful Improvements in Supports or Holders for Incandescent Electric Lamps; and I do hereby declare that the following is a full and exact description of the same.

According to my invention I use electric incandescent lamps of quite small dimensions, and mount the same upon a tubular support or holder of peculiar construction, the same presenting in a more or less perfect manner 10 the appearance of an ordinary candle. This holder is so arranged that it permits the lamp to be mounted and removed with great facility, and that the conducting-wires may be concealed from view. It will be seen that this 15 system of mounting incandescent electric lamps is particularly intended for application to the chandeliers, girandoles, &c., now in use, the advantage being that the forms and ordinary arrangements of such fixtures do not require 20 any changes.

The accompanying drawings form a part of this specification, and represent what I consider the best means of carrying out my invention.

Figure 1 is a central vertical section of my improved holders, showing a lamp in position. Fig. 2 is a horizontal section on the line $x-x$, Fig. 1. Fig. 3 is an elevation of the lamp detached.

On these drawings, a is a tubular holder, which may be made of porcelain, earthenware, opaque glass, or of metal, or any other suitable material capable of being painted or enameled, and which may, in shape, size, and color, 35 form as nearly as may be an imitation of an ordinary candle. This holder a carries at its top a very small incandescent lamp, b , and its lower end is screwed or otherwise firmly fastened in the socket c , which forms the extremity 40 of a chandelier-arm, or of any other fixture or device such are used for supporting candles. The upper part of the tubular holder is provided with a metallic ring, d , secured by cementing or other suitable means, and the lamp 45 b carries also a metallic ring, e , similarly secured, which may be locked into the former

by means of a bayonet-joint, as clearly shown in Figs. 1 and 2; or any other suitable means may be provided for locking the ring e into the ring d . The lower part of the holder a is 55 provided with a metallic socket, f , secured by cementing or otherwise, which is secured upon a correspondingly-threaded length of pipe, h , arranged centrally in the socket c . The tubular holder a is provided at or near the middle 60 of its length with an internal flange, k , which forms a bearing-point for a spiral spring, i , the object of which is to support the piece j . This piece j is made of insulating material, the conducting-wires g passing through the 65 same, and upon it is arranged in the ordinary manner the lamp b —that is to say, the conducting-wires g terminate in small hooks, to which the lamp is connected, as shown at i' in Fig. 1, the coiled spring i above the piece j 70 preserving the proper electric contact by the upward tension which it exerts on the lamp b , as will be understood. As soon as the lamp b is sufficiently turned to disconnect the bayonet-joint, the springs i i' push said lamp out 75 of the holder a , and the piece j also rises until it is arrested by the flange of the ring d , with the ends of the wires g projecting out so as to be easily accessible, thus permitting an examination of the lamp, and, if required, its removal and the substitution of another. 80

The interior of the tube a , below the flange k , forms a hollow, in which is arranged a sufficient length of conducting-wire, g , to allow the removal of the lamp and of the connected 85 piece j , when required. I form at the base of the tubular holder a openings m , through which, when it is impossible to completely conceal the conducting-wires in the arms and other parts of the chandelier or other fixtures 90 by passing them through the pipe h , said wires may emerge from the tube to be led along the exterior contours of the arms of the chandeliers or other fixtures.

It will be seen that by removing from the 95 socket c the pipe h and plate n upon which the base of the tubular holder a rests, this socket c may receive ordinary candles, no modification whatever being necessary in the general arrangement of the chandelier or other 100 fixture to which this system of lighting by electricity has been adapted.

It will be understood that the invention may be used in connection with any ordinary or desired style of incandescent lamp.

I claim as my invention—

- 5 1. The tubular holder *a*, having at its lower end a threaded portion, *f*, in combination with the socket *c*, having a removable plate, *n*, and a central pipe, *h*, for receiving said portion *f*, all arranged substantially as and for the purposes specified.
- 10 2. The tubular support *a* and inclosed spiral spring *i* and piece *j*, in combination with an incandescent lamp, *b*, suitable means for fastening the latter upon the holder *a*, and suitable means for connecting the same to the conductor, the piece *j* being located below the upper end of the spiral spring, so as to permit the upper portion of spring to exert an upward tension on the lamp, as and for the purposes herein specified.
- 15 3. The tubular support *a*, having an internal flange, *k*, dividing the space into two parts,

one for the reception of the spring *i* and the other for the reception of an extra length of conducting-wires *g*, in combination with said 25 spring and wires, and with an incandescent lamp, *b*, arranged upon the holder *a*, all substantially as and for the purposes herein specified.

4. The tubular support *a*, mounted upon a 30 socket, *c*, and carrying an incandescent electric lamp, *b*, said tubular support being provided at its base with holes *m*, adapted to allow the conducting-wires to be led from the exterior into and up through the hollow space 35 of the support to the lamp *b*, substantially as herein specified.

In testimony whereof I have signed this specification in the presence of two subscribing witnesses.

JEAN LANGUEREAU.
